UTILITY RACK

Louis A. Bell, St. Louis, Mo.

Application March 23, 1948, Serial No. 16,419

7 Claims. (Cl. 211—62)

1

This invention relates to new and useful improvements in utility racks, and the primary object of the present invention is to provide a combination umbrella, hat and magazine rack that is extremely neat and attractive in appearance.

Another important object of the present invention is to provide a movable rack including an umbrella receiving container or compartment embodying novel and improved means for draining rain water and the like that enters the umbrella receiving container resulting from the drippings of umbrellas inserted in the said container.

A further object of the present invention is to provide a utility rack including a support, and a novel improved garment holding element that is quickly and readily applied to or removed from the support in a convenient manner.

A still further aim of the present invention is to provide a utility rack that is simple and practical in construction, strong and reliable in use, small and compact in structure, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the utility rack constructed in accordance with the present invention;

Figure 2 is a longitudinal vertical sectional view taken substantially on the plane of section line 2—2 of Figure 1; and,

Figure 3 is a similar view of Figure 1, and showing the upright and garment supporting member removed therefrom.

Referring now to the drawings in detail, wherein for the purpose of illustration, there is disclosed a preferred embodiment of the present invention, the numeral 10 represents an outer article receiving container generally, having a multi-sided outer wall 12, a bottom wall 14, an inner multi-sided wall 16, and a plurality of spaced partitions 18 between each side of the said inner and outer walls 14 and 16, forming a plurality of circumferentially spaced magazine receiving compartments 20.

Integrally formed with the bottom wall 14 of the outer container 10 and projecting downwardly from a central opening provided in the bottom wall 14 is a hollow annular extension 22 having an annular flanged portion 24 that fric-

2

tionally engages an annular bearing ring 26 which is removably secured to the upper joined, central portion 28 of a plurality of radial, arcuate legs 30, the free ends 32 of which support casters 34.

Positioned within the outer container 10 and spaced relative to the inner wall 16 thereof, is a substantially frusto-conical inner container 36, the minor end of which is provided with a closure plate 38 that rests upon the bottom wall 14 of the outer container 10. Integrally formed with the central portion of the closure plate 38, is a depending sleeve or drain nipple 40 that engages the hollow extension 22 and which extends through an aperture 42 formed in the central joined portion 28 of the legs 30.

The numeral 44 represents an annular plate having a concaved upper surface 46 and a flat lower surface that bears upon the closure plate 38. Integrally formed with the lower surface of the plate 44, is a depending cylindrical element 48 having an axial bore that communicates with inclined drain apertures 50 provided in the plate 44. The central upper surface 46 of the plate 44 is integrally formed with a substantially vertical support or post 52 having a socketed upper end 54 that terminates in a plane spaced inwardly from the open upper end of the inner container. This socketed upper end 54 removably engages the reduced lower end 56 of an upright 58.

Fixed to the upper end 60 of the upright 58, is the central portion of a translucent, concavo-convex member 62 having a depending annular flanged portion 64 the outer surface of which supports a plurality of circumferentially spaced hooks or hangers 66. Removably secured to the upright 58, adjacent the upper end 60 thereof, is a support sleeve 68 that is fixed to the angulated reduced ends 70 of a plurality of circumferentially spaced, upwardly inclined radial support arms 72, the upper free ends 74 of which are angulated and are fixed to the inner surface of the flanged portion 64.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A utility rack comprising an outer container having an open upper end and a bottom wall, a flanged hollow extension carried by the bottom wall, a stand, means securing the flanged portion of the extension to said stand, an inner container within the outer container and having a bottom, and a sleeve depending from the bottom of the inner container extending axially through the flanged hollow extension to retain the inner container relative to the outer container, said sleeve forming a drain.

2. A utility rack comprising an outer container having an open upper end and a bottom wall, a flanged hollow extension carried by the bottom wall, a stand, means carried by the stand for rotatably engaging the flanged portion of the extension, an inner container having a bottom bearing upon the bottom wall of said outer container, a sleeve depending from the bottom of the inner container extending axially through the flanged hollow extension, said sleeve forming a drain, said outer container having inner and outer walls, the inner wall of said outer container loosely embracing the inner container.

3. The combination of claim 1 wherein said means securing the flanged portion of the extension to said stand includes a bearing ring frictionally engaging the flanged portion of the extension, a removably retaining ring carried by the bearing ring having an inner offset portion spaced from the bearing ring to overlie the flanged portion of the extension.

4. A utility rack comprising a stand having an axial bore, an outer container having a bottom wall with a central opening therein, a tubular extension depending from the bottom wall of said outer container about said opening and having a lower flanged portion, means carried by said stand rotatably supporting the flanged portion of said extension and centering the extension relative to the bore, an inner container including a bottom wall with a central aperture, a drain tube depending from the bottom wall of the inner container about the aperture and extending axially through the extension and the bore, a plate supported within the inner container and having a concave upper face, and a tubular element depending from the plate and entering the 50

drain tube, said plate having outlet apertures extending to the interior of said element.

5. A utility rack comprising a stand, inner and outer hollow members supported on the stand, said members each having a bottom wall, a sleeve depending from the bottom wall of the outer member and having an attaching flange secured to said stand, said stand having a vertical bore in registry with said sleeve, and a nipple depending from the bottom wall of the inner member extending axially through the sleeve and the bore and preventing lateral shifting of the inner member within the outer member.

15 6. A utility rack comprising a stand, inner and outer hollow members supported on the stand, said members each having a bottom wall, a sleeve depending from the bottom wall of the outer member and having an attaching flange secured to said stand, said stand having a vertical bore in registry with said sleeve, and a nipple depending from the bottom wall of the inner member extending axially through the sleeve and the bore and preventing lateral shifting of the inner member within the outer member, and means 20 25 removably secured to the stand and rotatably supporting said flange.

7. A display device comprising a base, a hollow holder including a bottom wall, a sleeve depending from the bottom wall of said holder and having a flange, means mounted on said base rotatably supporting said flange, another holder received within the first mentioned holder, said last named holder including a bottom wall, and a nipple depending from the bottom wall of said last named holder and extending through and rotatable in said sleeve.
